UNITED STATES PATENT OFFICE.

ROBERT D. EAGLESFIELD, OF INDIANAPOLIS, INDIANA.

FEEDING MECHANISM FOR MOLDING-MACHINES.

1,295,875.

Specification of Letters Patent.

Patented Mar. 4, 1919.

Application filed August 26, 1918. Serial No. 251,504.

To all whom it may concern:

Be it known that I, ROBERT D. EAGLESFIELD, a citizen of the United States, and a resident of Indianapolis, county of Marion and State of Indiana, have invented a certain new and useful Feeding Mechanism for Molding-Machines; and I do hereby declare that the following is a full, clear, and exact description thereof, reference being had to the accompanying drawings, in which like numerals refer to like parts.

This invention relates to improvements in molding machines and embodies subject matter excluded from my former application, Serial No. 190,579, filed September 10, 1917.

The prime feature of the invention is the provision of feed rollers arranged in pairs for feeding the timber to the planing and molding knives, and driving all of said rollers from a single driving means.

A further feature of the invention is the provision of means for adjusting one pair of rollers with respect to the other pair where-25 by timbers of varying thicknesses may be accommodated.

A further feature of the invention is the provision of means for holding the driving means at proper tension at all times without 30 directing tension on the driving means and at the same time permitting of ready adjustment of the rollers and parts carrying the same.

A further feature of the invention is the 35 provision of means for slightly canting all of the rollers and parts carrying the same whereby the timber passing between the rollers will have a tendency to move laterally in one direction as well as longitudinally.

A further feature of the invention is in so 40 mounting the upper set of rollers that they may have a tilting or swinging action so that when a heavier piece of timber is introduced between the first coöoperating set of rollers, the other rollers will continue to move the preceding piece of timber.

A further feature of the invention is the 45 provision of means for limiting the swing-50 ing movement of the upper set of rollers.

And a further feature of the invention is the provision of tensioning means for holding the swinging rollers in proper coöperating 55 position.

Other objects and advantages will be here-

inafter more fully set forth and pointed out in the accompanying specification.

In the accompanying drawings which are made a part of this application, Figure 1 is a vertical longitudinal sectional view 60 through a molding machine. Fig. 2 is a side elevation of that end of the molding machine containing the feeding device. Fig. 3 is a similar view of the opposite side of the machine. Fig. 4 is a sectional view as seen 65 in line 4—4, Fig. 1.

Referring to the drawings in which similar reference numerals designate corresponding parts throughout the several views, 1 indicates the frame of the molding machine 70 which may be of any preferred construction, and 2 indicates a bed plate mounted upon the frame and extending longitudinally thereof.

In order to move strips of timber longitudinally of the bed plate and in position to be engaged by the molding knives or cutters 3, the bed plate is provided with openings 4 through which project the edges of rollers 5 which are rotatably mounted upon shafts 6 80 immediately below the bed plate 2, the edges of said rollers projecting slightly above the upper face of the bed plate. Registering with the pair of rollers 5 and directly above the same is a pair of rollers 7 which are 85 mounted upon shafts 8, the ends of said shafts being in turn mounted in crossbars 9 which are in turn mounted upon a shaft 10 carried by standards 11, said crossbars being adapted to rock upwardly and downwardly 90 to permit the rollers 7 to accommodate themselves to timbers of varying thicknesses, the swinging movement of the crossbars being limited by placing lugs 12 on the outer faces of the crossbars at the opposite edges of the 95 standards 11. Extending across the rollers 7 are yokes 13 which are integral with the ends of the crossbars 9, said yokes forming bearings for tension springs 14 employed for normally holding the rollers 7 and parts 100 carrying the same against swinging motion, the upper end of the tension springs engaging a bar 15, adjustably mounted upon a stud bolt 16, which is in turn mounted upon the connecting bar 17 at the upper ends of 105 the standards 11. The stud bolt 16 is threaded to receive nuts 18 by means of which the bar 15 is adjusted on the stud bolt and the tension of the springs 14 increased or decreased.

The standards 11 are slidably mounted in guide plates 19 which are adjustably mounted upon the frame 1 by means of bolts 20 which extend through slots 21 in the guide plates 19 and into said frame.

The standards 11 and the rollers 7 carried thereby, are adjusted vertically through the medium of screw shafts 22 which are threaded through blocks 23 carried by the guide plates 19, the upper ends of the screw shafts extending through swivel blocks 24 on the standards 11. The upper ends of the screw shafts 22 are provided with bevel gears 25 with which mesh bevel gears 26 mounted upon a shaft 27 extending transversely through the upper ends of the standards 11, one end of the shaft having a crank or hand wheel 28 thereon, by means of which the shaft 27 may be readily rotated. By this construction the standards 11 and the rollers carried thereby can be readily and minutely adjusted vertically with respect to the rollers 5.

The upper and lower sets of rollers are operated from a single driving means which in this instance comprises an endless sprocket chain 29 which passes around a driving sprocket 30, rotatably mounted in the lower portion of the frame 1, one section of the chain passing upwardly and over gears 31 at one end of the rollers 5 and thence downwardly around a tensioning gear 32 rotatably mounted upon a bracket 33, thence upwardly over gears 34 at one end 35 of the rollers 7, and thence downwardly again to the driving sprocket 30, and it will be readily seen that when the driving sprocket 30 is rotated in the direction indicated by the arrow thereon, the lower rollers 40 5 will rotate to the left while the upper rollers 7 will rotate to the right, so that a piece of timber introduced between said rollers will be moved lengthwise. The bracket 33 is adjustably mounted upon one 45 of the standards 11 by introducing bolts 35 through elongated slots 36 in an angular extension 37 of the bracket 33, said bolts entering one edge of the standard, and owing to the elongated slots 36, the bracket and tensioning gear carried thereby may be adjusted so as to take up any slack in the sprocket chain 29 and by attaching the bracket direct to the standard, said bracket and the tensioning gear 32 will move upwardly and downwardly with the standard 55 11 when the standards are adjusted to adjust the rollers 7 with respect to the rollers 5, thus always maintaining the proper tension of the chain 29 without exerting pressure there- 60 against. The sprocket 30 is driven in any suitable manner, as by attaching a motor 38 thereto by means of a belt 39 and a driving pulley 40, or if preferred, the motor can be attached directly to the shaft 41 which carries the driving sprocket 30.

It is sometimes advisable to cause the timber passing between the rollers to crowd toward one or the other of the molding cutters, and in order to cause the timber to tend to travel laterally while moving longitudinally between the rollers, the bolts 20 are to be loosened and the guide plates 19 and standards 11 at one end of the rollers slightly canted or moved laterally out of direct alignment with the guide plate at the opposite side of the machine, depending upon which direction it is desired to have the timber moved laterally, thereby disposing both sets of rollers at a slight angle to the direction of travel of the timber, and consequently causing the timber to crowd toward one edge of the bed plate, and by canting both sets of rollers, but a very slight movement of the rollers at one end is required to accomplish the desired result.

The invention claimed is:

1. In a feeding mechanism for molding machines, the combination with feed rollers arranged in pairs, one above the other, and means to adjust the upper pair of rollers vertically, of a single driving chain for operating both pairs of rollers, and a tensioning gear movable vertically with said upper pair of rollers for retaining said driving chain at a uniform tension without directing pressure thereagainst.

2. In a feeding mechanism for molding machines, the combination with a frame, of guide plates, standards coöperating with the guide plates, and two pairs of coöperating rollers one above the other, one pair of rollers being carried by the guide plates and the other pair by the standards, and means to adjust the guide plates on the frame, whereby both sets of rollers may be canted to cause objects passing therebetween to move laterally as well as longitudinally.

3. A feeding mechanism for molding machines, comprising a pair of guide plates, a pair of rollers carried by the guide plates, a standards adjustably attached to the guide plates; a pair of rollers carried by the standards, and above the first pair of rollers, a single driving chain for all of said rollers and a tensioning gear carried by one of the standards and so arranged that the chain will be held at a uniform tension without engaging the tensioning gear with said chain under pressure.

4. In a feeding mechanism for molding machines, the combination with a pair of guide plates, a pair of standards coöperating with the guide plates and a bar connecting the upper ends of said standards, of a shaft extending transversely through said standards centrally below said connecting bar, a pair of crossbars pivotally mounted on said shaft, one adjacent each standard, and projecting an equal distance on each side of said shaft, a yoke integral with each

end of said crossbars, means for limiting the swinging movement of said crossbars, comprising a stud bolt projecting upwardly from the longitudinal center of said connecting bar for the standards, a bar slidable on the stud bolt and extending transversely of said connecting bar and having its ends over the longitudinal center of said yokes,

means to vertically adjust said bar on the stud bolt, and vertically disposed coiled tensioning springs between the ends of said adjustable bar and said yokes.

In witness whereof I have hereunto affixed my signature.

ROBERT D. EAGLESFIELD.
